CLAIM

The ornamental design for a mobile phone, as shown and described.

DESCRIPTION

FIG. 1 is a rear perspective view of a mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The evenly spaced broken lines shown in the figures that are immediately adjacent to the areas included in the claim and define unshaded regions, and the dot-dash broken lines shown in the figures, represent the bounds of the claim. All other broken lines, including the features within broken line boundaries, are directed to environment. The broken lines form no part of the claimed design.
